UNITED STATES PATENT OFFICE

169,134

MEDAL

Laura Gardin Fraser, Westport, Conn., assignor
to United States Military Academy, West Point,
N. Y.

Application August 22, 1951, Serial No. 16,407

Term of patent 3½ years

(Cl. D29—19)

To all whom it may concern:

Be it known that I, Laura Gardin Fraser, a citizen of the United States of America and residing in Westport, county of Fairfield, State of Connecticut, have invented a new, original, and ornamental Design for a Medal, of which the following is a specification, reference being had to the accompanying drawing, forming a part hereof.

Fig. 1 is a front elevational view of a medal showing my new design; and

Fig. 2 is a side elevational view thereof.

The dominant features of my new design are those residing in the portions shown in full lines in the drawing.

The side of the medal not shown in the drawing is plain.

I claim:

The ornamental design for a medal, as shown and described.

LAURA GARDIN FRASER.
